OIL BURNER

William M. Esterling, Long Beach, Calif., assignor, by direct and mesne assignments, of fifteen per cent to Henry Walters, fifteen per cent to Mary P. Walters, five per cent to Charles Kling and/or Ida M. Kling, eighteen per cent to Bessie M. Cone, two per cent to Z. B. West and Franklin G. West, known as West & West, and twenty per cent to Ruben F. Wussow, Santa Ana, Calif.

Application August 7, 1931, Serial No. 555,672

3 Claims. (Cl. 299—131)

This invention relates to a burner, and relates more particularly to a fluid fuel burner for use on a boiler, or the like. It is a general object of the present invention to provide a simple, practical, and effective burner of the general character referred to.

Another object of the invention is to provide a burner for handling a fluid fuel, such as oil, at high pressures.

10 It is another object of the invention to provide a burner embodying means for heating the fuel before it is discharged from the nozzle.

Another object of the invention is to provide a burner of the character mentioned that operates to discharge the fuel in a conically-shaped stream and in an atomized condition.

15 It is a further object of the invention to provide a burner of the character mentioned that may be easily and quickly altered or converted for use in various installations and situations. It is a feature of the present invention that the burner may be shortened to the desired length during its installation by cutting only a rod and a pipe.

20 Another object of the invention is to provide a burner of the character mentioned that may be readily adjusted or regulated to properly handle the fuel at different pressures, etc., and to discharge the fuel in the desired manner and in the desired quantities.

25 A further object of the invention is to provide a burner of the general character mentioned that is particularly simple and inexpensive of manufacture.

30 Other objects and features of the invention will be best and more fully understood from the following detailed description of a typical form and application of the invention, throughout which description reference will be had to the accompanying drawing, in which:

35 Fig. 1 is a side elevation of the burner provided by this invention. Fig. 2 is an enlarged longitudinal detailed sectional view of the device, and Fig. 3 is an enlarged transverse detailed sectional view taken as indicated by line 3—3 on Fig. 2.

40 The burner provided by my present invention includes, generally, a body 10, an extension 11 on the body carrying a nozzle head 12, means 13 for controlling the discharge of fuel from the nozzle head 12, and means 14 for heating the fuel during its passage through the burner.

45 The body 10 of the burner is provided to carry the extension 11 and the principal parts of the control means 13. The body 10 may be in the form of an integral member or casting, and is cylindrical in its general configuration. A cen-

tral longitudinal opening 15 extends completely through the body from one end to the other. The body opening 15 has portions of various diameters, as will be hereinafter described.

5 A lateral fuel inlet port 16 communicates with the body opening 15 adjacent the inner end of the body. The port 16 extends outwardly through a lateral boss 17. The fuel may be delivered to the port 16 through a supply conduit 18. Suitable packing means may be provided at the boss 17 to seal about the end of the conduit 18. In the particular embodiment of the invention disclosed in the drawing the packing means for sealing about the fuel conduit includes a body 19 of packing arranged against the end of the boss 17 and surrounding the conduit 18, and a gland or follower 20 screw threaded on the boss 17 to compress the packing.

10 The body extension 11 is provided to carry the nozzle head 12 and to deliver or pass fuel to the nozzle head. Further, the extension 11 operates to support the heating means 14, as will be hereinafter described.

15 In accordance with the preferred form of the invention, the extension 11 is in the nature of a simple length of pipe or tubing. The extension 11 may be of any suitable length, depending upon the use or application of the burner. It is preferred to initially form the extension 11 comparatively long so that it may be shortened to any desired length when the burner is installed. It is a feature of the invention that the extension 11 has a detachable connection with the body 10. The outer end of the extension 11 is screw threaded into a socket 21 in the inner end of the body 10. The opening 22 in the extension 11 extends completely through the extension from one end to the other and is preferably of substantially the same diameter as the end portion of the body opening 15.

20 The nozzle head 12 is mounted on the end of the body extension 11. In the preferred construction the nozzle head 12 is detachably screw threaded to the extension. In the particular case illustrated in the drawing the nozzle head 12 is provided with a screw threaded socket 23 to receive the end of the extension 11. The head 12 is provided with a central longitudinal opening 24 to discharge the fuel. The opening 24 is of considerably less diameter than the opening 22 of the extension, and its outer end portion 25 is restricted or reduced in diameter. The outer end portion of the nozzle opening is round in cross section and is rather short, and its walls are flared or outwardly divergent. The nozzle

head 12 may be suitably shaped, for example, it may have an outwardly convergent exterior and a flat outer end.

The means 13 is manually operable or adjustable to control the discharge of fuel from the nozzle 12 and operates to cause the atomization of the fuel as it is discharged from the nozzle. The control means 13 includes a flow controlling member or control head 26, a stem 27 carrying the head 26, and means 28 for operating the stem 27. The control head 26 is disposed within the restricted portion 25 of the nozzle opening and operates to cause the breaking up or atomizing of the fuel as it is discharged from the nozzle under pressure. The control head 26 includes a main portion or body 29. The body 29 of the control head is frusto-conical, having outwardly divergent walls pitched at the same angle as the walls of the nozzle opening 25. The body 29 of the control head is proportioned so that it may effectively seat against or cooperate with the walls of the opening 25 under certain operating conditions. An inwardly-projecting screw-threaded stem or screw 30 is provided on the control head 26 for connection with the stem 27. A slotted projection 31 may be provided on the outer end of the control head 26 to facilitate the mounting and removal of the control head.

The stem 27 is an elongated rod extending through the extension 11 and into the body 10. The stem 27 is round in cross sectional configuration and is movable longitudinally by the means 28. An end portion of the stem 27 is slidably in the opening 24 of the nozzle head. The opening 24 operates to slidably guide and center the stem. A screw-threaded opening 32 is provided in the end of the stem 27 to receive the screw 30 of the control head. The end portion of the stem 27 extending into the nozzle opening 24 is fluted or provided with spaced longitudinal grooves 33. The grooves 33 are provided to pass the fuel from the opening 22 of the extension to discharge through the nozzle head. The stem 27 extends through the body opening 15 and is slidably guided and centered by a reduced portion 33a of the body opening. It is to be noted that the openings 24 and 33a operate to slidably support the stem 27 at longitudinally spaced points so that it is effectively centered and guided.

The means 28 for operating or shifting the stem 27 includes an operating member 34 extending into an opening 35 in the body 10. A pin 36 is provided on the operating member 34 and is screw threaded into the body opening. A suitable hand wheel or disc-shaped enlargement 37 is provided on the outer end of the operating member 34 to facilitate the manual turning or operation of the member. The stem 27 extends through a central longitudinal opening 38 in the operating member 34. The stem 27 is freely rotatable in the opening 38. The stem 27 is connected with the operating member 34 so as to move longitudinally together with the operating member. The outer end portion of the opening 38 is of enlarged diameter, and a collar 39 is provided on the end of the stem 27 within the enlarged portion of the opening. The collar 39 may be fixed on the stem 27 in any suitable manner. A plug 40 is threaded into the outer end of the opening 38 and engages the end of the stem 27 to retain the collar 39 against the outwardly-facing shoulder 41. It will be apparent how operation or threading of the operating member 34 causes longitudinal movement of the stem 27. The stem 27 may not turn or rotate during operation of

the member 28, as the stem is rotatably carried in the opening 38.

The invention includes means for sealing about the stem operating member 34. Packing 42 is arranged in a socket in the end of the body and surrounds the member 34. A follower 43 surrounds the member 34 and engages the packing 42. A gland or cap 44 is screw threaded onto the end of the body 10 and engages the follower 43 to force it against the packing 42.

The heating means 14 is operable to heat the fuel during its passage through the body extension 11, so that it may have the desired fluidity when discharged from the burner. Warming or heating of the fuel during its passage through the extension 11 renders it more fluid, so that it is effectively broken up or atomized when discharged from the nozzle. A plurality of heating units 45 are arranged on the extension 11. The units 45 are annular or tubular structures, each including a shell 46, a heating element 47 within the shell, and suitable insulating material 48 encasing the heating element. The several heating units 45 are alike or similar in construction and are removably retained on the extension 11. There may be any suitable number of heating units 45, there being four units in the specific embodiment of the invention illustrated in the drawings. The several heating units 45 may be separate or individual devices and may be electrically connected by suitable connections 49. The heating units 45 are clamped between the inner end of the body 10 and the nozzle head 12. Spacers 50 may be arranged between the several heating units 45. It will be apparent how the heating units 45 are clamped or retained on the extension 11 between the body 10 and the screw-threaded nozzle head 12. The heating units 45 in surrounding the extension 11 are particularly effective in heating the fuel during its passage through the opening 22 of the extension.

It is believed that the utility and practicability of the burner provided by my present invention will be readily apparent from the foregoing detailed description. The burner is particularly adapted to handle fuel under high pressures, and the control head 26 may be set or adjusted to provide for the desired discharge of the fuel. The burner may be operated at pressures in the neighborhood of 2000 pounds per square inch. The operating member 28 may be manually operated to set the control head 26 in any desired position. Where the fuel is handled at very high pressures, the body 29 of the control head may be seated against the walls of the opening 25. The seating of the body 29 of the control head in the nozzle opening may be hand-tight, that is, the operating member 28 may be manually operated to seat the head 26 in the opening with the desired force. The fuel under pressure tends to stretch or elongate the control head 26 and issues from between the head 26 and the walls of the opening 25 in an extremely fine spray. It is to be understood that the control head 26 may be set in any desired or suitable position, depending upon the character of the fuel, the pressure under which the fuel is handled, etc. The heating units 45 operate to warm or heat the fuel during its passage through the burner so that it is made more fluid to be readily broken up when discharged from the nozzle head 12. The burner may be readily adapted for any particular installation, as the extension 11 and the rod 27 may be cut to the desired sizes to suit the burner for any particular situation. The detachable extension 11

and the stem 27 may be cut and fitted during the installation of the burner. If the extension 11 is shortened when the burner is installed, it is only necessary to cut threads on its end so that 5 it may be attached to the body 10. If the stem 27 is shortened, the collar 39 is fixed on the end of the stem so that the stem carries the control head 26 in the desired position. The present invention provides a burner that is particularly 10 simple and inexpensive of manufacture and a burner that is readily capable of installation in various situations.

Having described only a typical preferred form 15 of my invention, I do not wish to limit myself to the specific details set forth, but wish to reserve to myself any changes or variations that may appear to those skilled in the art or fall within the scope of the following claims.

Having described my invention, I claim:

20 1. In a device of the character described, a body having an opening, an oil inlet communicating with the opening, a tubular member threaded into the opening and having a socket in its outer end, the inner end of the socket forming a shoulder, a flow controlling stem rotatably passing through the tubular member for controlling the discharge from the opening, a collar on the stem in the socket, a plug threaded into the socket, the shoulder and plug cooperating with the col-

lar whereby the stem is movable longitudinally with the member, and a handle on the member whereby the member may be threaded into and out of the body to operate the stem longitudinally.

2. An oil burner including a body having a longitudinal passage, an oil inlet communicating with said passage, a stem shiftably guided in said passage, a valve head threadedly connected with the stem for cooperating with said passage, 10 rotatable means for longitudinally shifting the stem and controlling the discharge from said passage, and a swivel connection between the stem and said means allowing relative rotation.

3. An oil burner including a body having a longitudinal passage, an oil inlet communicating with said passage, a nozzle on the end of the body in register with said passage, a stem arranged in said passage, having one end shiftably guided by the nozzle and its other end by the body, a 20 valve head threadedly connected with the stem for cooperating with the nozzle, rotatable means on the body for longitudinally shifting the stem and controlling the discharge from said passage, and a swivel connection between the stem and 25 said means allowing relative rotation.

WILLIAM M. ESTERLING.
